UNITED STATES PATENT OFFICE.

NELSON W. THOMPSON, OF OAKLAND, AND FRANK J. McGRAW, OF MARTINEZ, CALIFORNIA, ASSIGNEES, BY MESNE ASSIGNMENTS, TO SHELL COMPANY OF CALIFORNIA, OF SAN FRANCISCO, CALIFORNIA, A CORPORATION OF CALIFORNIA.

PUMP.

1,275,793.

Specification of Letters Patent. Patented Aug. 13, 1918.

Application filed July 2, 1917. Serial No. 178,269.

To all whom it may concern:

Be it known that we, NELSON W. THOMPSON and FRANK J. McGRAW, both citizens of the United States, the former residing at 5 Oakland, in the county of Los Angeles and State of California, (whose post-office address is 6019 Hillegass avenue, Oakland, Alameda county, California,) and the latter residing at Martinez, in the county of Contra Costa and State of California, (whose post-office address is P. O. Box 581, Martinez, Contra Costa county, California,) have invented a new and useful Pump, of which the following is a specification.

15 Our invention relates to pumps, and the principal object of the invention is to provide a pump which may be used in conjunction with oil cracking apparatus.

It is common practice in the petroleum industry to subject oils to considerable temperatures and pressures for the purpose of changing their chemical characteristics, or more specifically for the purpose of lowering their boiling point and increasing their 20 volatility. When oils are subjected to the proper conditions to accomplish this considerable deposits of carbon often take place, and this carbon readily deposits and adheres to metal surfaces. It is often necessary in 25 operation of such systems to pump the residual of such cracking processes while still hot and while under considerable pressure. The ordinary forms of pumps are unsuited to this work as the valves thereof become 30 clogged by carbon deposits and the pump soon becomes inoperative. The greatest trouble in operating said pumps is found with the inlet valve.

The principal object of our invention is 35 to provide a pump which is especially adapted to work in conjunction with the stills used in such cracking processes.

Further objects and advantages will be made evident hereinafter.

45 Referring to the drawings, which are for illustrative purposes only:

Figure 1 is a plan view of apparatus adapted for this particular service.

Fig. 2 is an elevation, partly in section, 50 on a plane represented by the line 2—2 of Fig. 1.

In the embodiment of our invention shown in these drawings, a conical bottom 11 of a cracking still is shown connected by means

of flanges 12 and 13 with an injector ring 55 14 and a pump casing 15. The pump casing 15 comprises walls inclosing an inlet opening 16 registering with an outlet opening 17 of the still 11, and walls forming piston cylinders 18, which are coaxial with each 60 other and at approximately right angles to the vertical axis of the still. Sliding in the cylinders 18 are pistons 19 which are actuated through a suitable piston rod 20 by any sort of suitable reciprocating mechanism, 65 not shown, the piston rod 20 passing through a stuffing box 21. Communicating with the outer ends of each of the cylinders 18 is a pump outlet opening 22 which is provided with a ball valve 23 and a discharge flange 70 24. The discharge flanges 24 are connected to a common outlet pipe, not shown, through which the hot residuum may be forced back into the still 11 or may be delivered to any other suitable apparatus. Secured 75 to the pistons 19 and extending upwardly through the openings 16 and 17 are stirring rods 30. These rods serve to break up any carbon deposited and prevent it from choking the openings 16 and 17. Connected 80 into each of the outlet pipes above the valve 23 is a recirculating pipe 40, each of these pipes being provided with a valve 41 and being connected into the injector ring 14 on either side thereof.

85 The method of operation of our invention is as follows:

The pistons 19 being reciprocated in the cylinders 18, the stirring rods 30 are also reciprocated moving from side to side in 90 the openings 16 and 17 and effectually preventing any accumulation of carbon therein. The pistons 19 form their own inlet valves, forcing residuum through the valves 23 on the pressure stroke and causing a slight 95 vacuum under the valve 23 on the return stroke, and this vacuum is immediately filled with hot residuum as soon as the piston 19 reaches a point where the interior of the cylinders 18 and the opening 16 are in full 100 communication with each other. The pistons 19 are run considerably faster than is necessary to handle the full capacity of the still 11, and the valves 41 are partially open allowing the residuum under pressure to be 105 continuously forced through the pipes 40 and the injector ring 14 into the opening 17. This rapid and continuous flow further

tends to prevent any deposits of carbon in the opening 17.

We claim as our invention:—

1. In combination; a cracking still; a pump taking liquid from said still through an opening in the bottom of said still; stirring rods projecting into said opening; and means by which said pump actuates said rods.
2. In combination; a cracking still having a discharge opening therein; a pump taking liquid from said still through said opening; and pipe means connected to the pressure side of said pump and so arranged that oil from said pump is injected under pressure into said opening to prevent carbon deposits therein.
3. In combination; a cracking still having a discharge opening therein; a pump taking liquid from said still through said opening; stirring rods projecting into said opening; mechanism by which said pump actuates said stirring rods; and pipe means

connected to the pressure side of said pump and so arranged that oil from said pump is 25 injected under pressure into said opening to prevent carbon deposits therein.

4. In combination; a cracking still having a discharge opening therein; a pump casing having walls inclosing a pump inlet opening registering with and forming a continuation of said discharge opening; walls forming two cylinders coaxial with each other and in open communication with said pump inlet opening; pistons moving in said cylinders; stirring means attached to said pistons and projecting through said pump inlet opening into said discharge opening; and a discharge valve in the end of each cylinder.

In testimony whereof, we have hereunto set our hands at the city and county of San Francisco, State of California, this 15th day of June, 1917.

NELSON W. THOMPSON.
FRANK J. McGRAW.
